BEATER ELEMENT FOR PULVERIZING APPARATUS

Ollison Craig, Worcester, Mass., assignor to Riley Stoker Corporation, Worcester, Mass., a corporation of Massachusetts

Application December 28, 1940, Serial No. 372,102

4 Claims. (Cl. 83—11)

This invention relates to beater elements for pulverizing apparatus, and is an improvement over the construction disclosed in the patent to Armour, No. 1,941,923, dated January 2, 1934.

The beater elements disclosed in said prior patent are adapted for use in pulverizing apparatus of the general type shown in my prior Patent No. 1,714,080, dated May 21, 1929. These elements comprise a rotor wear plate shaped as a circular ring sector, with a peg extending from one face of the plate near its outer peripheral edge, and a pair of pegs extending from the said face and spaced inwardly from the first peg toward the axis. All the pegs are located in a symmetrical arrangement relative to the radial center line of the plate. At assembly each of the inner pegs is located closely adjacent to a peg on the adjoining element, and in effect these two adjacent small pegs form a single large peg having two separable halves. In the operation of the machine one of these halves is located in front of the other and hence is subjected to much more rapid wear from the abrasive action of the material being pulverized. When this wear has become sufficiently extensive to weaken the front half of the peg so that there is danger of this half breaking away from the plate and possibly wrecking the machine, it is necessary to replace the entire element, even though the rear half of the peg may be scarcely worn at all. Consequently an appreciable expense is involved for replacement parts in order to maintain the machine in proper operating condition.

It is accordingly one object of the invention to provide a beater element which will have a longer life of useful service than elements heretofore utilized.

It is a further object of the invention to provide a beater element of the type having a wear plate and pegs projecting therefrom so constructed that the pegs may become considerably worn without danger of their breaking away from the plate.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is an elevation of a portion of a pulverizer rotor, viewed from the discharge side;

Fig. 2 is a section on the line 2—2 of Fig. 1; and

Fig. 3 is a perspective view of one of the beater elements removed from the rotor.

The embodiment illustrated in the drawing comprises a flat circular rotor disk 10 which is identical with the disk disclosed in my prior Patent No. 1,714,080 and is intended to be rotatably mounted in a pulverizing apparatus of the same general type as that shown in said patent. The peripheral portion of this disk at the 10 side toward the pulverizer inlet (not shown) is protected by means of wear plates 11 (Fig. 2) which may be of the same general construction as the corresponding parts shown in my said patent. The beater elements 12 on the opposite 15 side of the disk are the subject matter of the present invention.

Each beater element 12 comprises a wear plate 14 having an inner edge 15 and an outer edge or periphery 16. These edges 15 and 16 are shaped as concentric circular arcs having their common center on the axis of the disk 10, the two edges being offset from one another in a circumferential direction. The edges 15 and 16 are connected by two straight inwardly-converging side edges 18 both of which are located on lines 20 (Fig. 1) tangential to a common circle 21, this circle being concentric with the arcs 15 and 16. Thus the plate may be described as a circular ring sector with its inner and outer edges offset in a circumferential direction. A flange 23 is provided on the rear face of each plate adjacent the outer edge 16 thereof, this flange overlying the outer edge of the disk 10 at assembly, as shown in Fig. 2. A cylindrical projection 24 extends from the rear face of the plate and fits an opening in the disk, thereby serving to locate the plate properly on the disk.

The plates 14 are bolted to the rotor disk, and for this purpose a half bolt hole 26 is provided on each side edge 18 thereof near the outer edge 16, and a bolt hole 27 is provided inwardly of the holes 26 and on the radial line midway between the same. These bolt holes 26 and 27 are provided with cylindrical counterbores 28 and 29 respectively to receive the hexagonal nuts 31 of plow bolts 32 which secure the plates 14 and 11 to the disk.

Pulverization of the material passing through the machine is effected by the action of pegs extending from the front or exposed faces of the plates. In the embodiment illustrated each plate is provided with two integral projecting pegs. One large peg 34 of substantially rectangular cross section is located adjacent the outer edge 16 of the plate and midway between the two bolt

holes 26. One somewhat smaller peg 35 of substantially rectangular cross section is located between the inner bolt hole 27 and the side edge more remote therefrom. The inner peg 35 is offset from the outer peg 34 in the same direction as the inner edge 15 of the plate is offset, and the bolt hole 27 is in substantial radial alignment with the outer peg. It will be apparent from Fig. 1 that at assembly the pegs 34 and 35 provide outer and inner annular rows of pegs. In each row the bolts alternate with the pegs, so that the bolts are well protected from abrasion regardless of the direction of revolution, and right and left constructions are unnecessary.

Because of the circumferential offsetting of the inner and outer edges of the plate, the inner peg 35 can be made of sufficient size to ensure a long life of useful service. Since there is no need for forming this peg of two parts located on separate elements, the beater elements can safely remain in use for much longer periods than has been possible with prior constructions.

Having thus described my invention, what I claim as new and desire to secure by Letters Patent is:

1. A beater element for a pulverizing apparatus comprising a rotor wear plate having inner and outer edges shaped as concentric circumferentially-offset circular arcs and two straight inwardly converging side edges located on lines tangential to a common circle concentric with the said arcs, and a peg projecting from one face of the plate.

2. A beater element for a pulverizing apparatus comprising a rotor wear plate having its outer periphery offset circumferentially from its inner

edge, the plate having a half bolt hole at each side edge adjacent its outer periphery and a bolt hole located inwardly of the half bolt holes and on the radial line midway between the same, a peg projecting from the plate adjacent the outer periphery and between the half bolt holes, and a peg projecting from the plate between the inner bolt hole and the side edge more remote therefrom.

3. A beater element for a pulverizing apparatus comprising a rotor wear plate having inner and outer edges shaped as concentric circumferentially-offset circular arcs and two straight inwardly converging side edges located on lines tangential to a common circle concentric with the said arcs, the plate having a half bolt hole at each side edge adjacent its outer periphery and a bolt hole located inwardly of the half bolt holes and on the radial line midway between the same, a peg projecting from the plate adjacent the outer periphery and between the half bolt holes, and a peg projecting from the plate between the inner bolt hole and the side edge more remote therefrom.

4. A beater element for a pulverizing apparatus comprising a rotor wear plate shaped as a circular ring sector with its inner and outer edges offset in a circumferential direction, a peg projecting from the plate adjacent its outer periphery, the plate having bolt holes on opposite sides of the peg, and a second peg projecting from the plate inwardly of the first peg and offset therefrom in the same direction as the inner edge of the plate is offset, the plate having a bolt hole located at one side of the second peg and in substantial radial alignment with the first peg.

OLLISON CRAIG.
